(57) **CLAIM**

The ornamental design for a removable jar of a portable blender, as shown and described.

DESCRIPTION

FIG. 1 is a front view of a removable jar of a portable blender showing the new design;

FIG. 2 is a left-side view thereof, the right side view being a mirror image;

FIG. 3 is a rear view thereof;

FIG. 4 is a top view thereof; and,

FIG. 5 is a front-left perspective view thereof.

The portions shown in broken lines form no part of the claimed design.

1 Claim, 5 Drawing Sheets
